KNOWLSON TOWNSEND, OF SAN FRANCISCO, AND ROBERT HILL, OF OAKLAND,
CALIFORNIA

OIL BURNER

Application filed May 15, 1930. Serial No. 452,757.

Our invention relates to improvements in oil burners, and more particularly to atomizers for oil burners, and the principle of which may be used for other purposes, such as gas and air burners, water sprinklers and the like.

In oil burners of the type using oil which is preheated and under pressure, thorough atomization and spreading is required for the most efficient heat in the furnace, and the object of this invention is to provide an atomizer of greater efficiency.

Another object is to improve the construction of the tip or nozzle to receive the atomizer element and to provide means of clamping the two on the end of an oil feed pipe.

Another object is to provide a double thread to give the oil a rotary as well as forward movement, and at the same time avoid the retarding effect on the flow of oil.

Other objects will appear to those skilled in this art as the description progresses.

An embodiment of the invention is shown in the accompanying drawings in which the same reference numeral is applied to the same portion throughout the several views, and of which there may be modifications:

Figure 1 is a side elevation of the assembled burner.

Figure 2 is an end view of the tip end of the burner somewhat enlarged.

Figure 3 is an enlarged sectional view showing the construction of the tip, atomizer and clamping nut, on the end of a pipe, and

Figure 4 is a detached, enlarged, end view of the atomizer.

The numeral 1 indicates the head of the burner, into which is screwed the pipe 2 threaded at both ends, as shown at 3 and 4. On the end thread 4 is a clamping nut 5. The atomizer consists of the flange 6, having the stud 7 integral therewith, the end of the stud being cone shaped as at 8. On the stud are formed square double threads 9 and 10 forming the grooves 11 and 12 through which the oil flows from the hole 13 which receives the oil from the pipe 14 through the opening 15. The tip 16 has the flange 17, which is clamped against the flange 6 on the end of the pipe. The opening 18 fits over the

outside of the threads, and cone shaped opening 19 allows space around the cone 8, for the flow of oil around the cone, and through the tip opening 20. In operation the oil flows from the pipe through the openings 15 and 13 and comes out on both sides of stud and is whirled around the grooves 11 and 12 and out over the cone, and through the tip opening which imparts a rotary or whirling motion just before it reaches the tip hole, and it leaves the tip-opening in a cone shaped spray, and thus a very efficient heating flame is produced.

The use of two square threads was found to be more efficient than a single thread or a number of threads in the atomizer.

Having thus described our invention, what we desire to secure by Letters Patent of the United States is as follows, but modifications may be had in carrying out the invention as shown in the drawings and in the above particularly described form thereof within the purview of the annexed claims.

We claim:

1. An oil burner comprising in combination an oil supply pipe, a flanged member on the end of said pipe, a stud on said flanged member, double screw threads on said stud, a transverse opening through said stud leading to each of said threads, said opening having a connection with the oil supply pipe, a flanged tip mounted on said flanged member, and means to clamp both of said flanges to the end of the pipe.

2. An oil burner comprising a flanged atomizer, a flanged tip fitting over said atomizer, and both flanges one on the other being clamped to the end of an oil supply pipe.

KNOWLSON TOWNSEND.
ROBERT HILL.
